UNITED STATES PATENT OFFICE.

ALBERT COWELL, OF KIDDERMINSTER, ENGLAND.

DESIGN FOR A CARPET-PATTERN.

Specification forming part of Design No. 5,884, dated June 4, 1872.

To all whom it may concern:

Be it known that I, ALBERT COWELL, of Kidderminster, Worcestershire, in England, have invented a new and original Design for Carpets; and I do hereby declare that the following is a full, clear, and exact description thereof, which will enable others skilled in the art to make and use the same, reference being had to the accompanying photographic illustration forming part of the specification.

The nature of my invention is fully represented in the accompanying photographic illustration, to which reference is made.

This invention relates to a new carpet design, which embraces a new octagonal center piece, a new form of smaller central figure, and a new kind of background surrounding

the smaller figure. This background is composed of ornamental scrolls, resembling the letter **S** naturally and in reversed position. The smaller central figure, which they surround, consists of four heart-shaped projections around a circular center. The larger octagonal figure has a mixtilinear outline, and eight outer tufts which resemble somewhat those of the smaller figure. The center of the octagon is square, and has cross-shaped projections, as shown.

I claim as my invention—

The design for carpets, as shown.

ALBERT COWELL.
